UNITED STATES PATENT OFFICE

93,204

DESIGN FOR A PULL FOR SLIDE FASTENERS

Alfred E. Carlile, Meadville, Pa., assignor to
Hookless Fastener Company, Meadville, Pa., a
corporation of Pennsylvania

Application July 12, 1933, Serial No. 48,698

Term of patent 14 years

To all whom it may concern:

Be it known that I, ALFRED E. CARLILE, a citizen
of the United States, residing at Meadville, in the
county of Crawford, and State of Pennsylvania,
have invented a new, original, and ornamental
Design for a Pull for Slide Fasteners, of which
the following is a specification, reference being
had to the accompanying drawing, forming a part
thereof.

In the drawing.

Fig. 1 is a plan view of a pull for slide fasteners
showing my new design;

Fig. 2 is a side view of the same.

I claim:

The ornamental design for a pull for slide
fasteners as shown.

In testimony whereof I affix my signature.

ALFRED E. CARLILE.
